UNITED STATES PATENT OFFICE

2,048,496

ELECTRICAL SWITCH GEAR

Arthur Charles Ehrenberg, Timperley, England,
assignor to General Electric Company, a corporation of New York

Application January 10, 1934, Serial No. 706,142
In Great Britain January 20, 1933

6 Claims. (Cl. 200—150)

The invention relates to electrical switchgear and has for its object the provision of an improved switch or circuit breaker of the double break type suitable for use in connection with 5 currents of high voltage.

According to the invention the fixed contact and terminal structures of the switch are housed in separate oil filled chambers or casings each of which is insulated suitably to withstand continuously the voltage between the electric line conductors and ground, and the space between the two casings is bridged by a pair of electrical insulating oil filled bushings or insulating shells placed end to end and united by a junction box or intermediate casing, which is also insulated with respect to line potential and ground. The moving contacts with their supports and associated operating devices or rods are located within the bushings and their operation is controlled or effected from the intermediate casing which joins the ends of the bushings.

In carrying out the invention the intermediate and terminal casings may be supported on hollow insulating columns or pillars of which at least those for the terminal casings are filled with oil or other insulating fluid. In some cases the instrument or relay transformers or other apparatus associated with the switches may be accommodated within said columns. The movable contacts may be actuated by pneumatic, hydraulic, mechanical or other means, these devices being operated or controlled through the intermediate casing so that the two contacts will be actuated substantially simultaneously to effect a double break in the circuit. Where compressed air is employed as the actuating means the conduits for the same may be carried within or by the insulating column of the intermediate casing and the distributing and exhaust valves controlling the operation may be located within the said casing and operated from the ground level by insulating mechanical connections.

My invention will be more fully set forth in the following description referring to the accompanying drawings, and the features of novelty which characterize my invention will be pointed out with particularity in the claims annexed to and forming a part of this specification.

A pneumatically operated double break switch or circuit breaker suitable for voltages over 100,000 volts, and constructed according to the invention 55 will now be described by way of example, with

reference to the accompanying drawings, in which,

Fig. 1 is an elevational view of the switch.

Fig. 1A is an enlarged view, partly in section, of a portion of the switch shown by Fig. 1. 5

Fig. 2 is a front view of a switch tank detail drawn to an enlarged scale.

Fig. 3 is a section on the line A—A of Fig. 2.

Fig. 4 is a section on the line B—B of Fig. 2.

Fig. 5 is an elevation partly sectional of the compressed air valve operating mechanism, drawn to an enlarged scale and.

Fig. 6 is a small scale plan view of the arrangement of switch or circuit breakers constructed according to the invention for a three-phase system.

Referring more particularly to Figs. 1 and 1A, the double-break switch or circuit breaker comprises relatively movable contacting members 1, 2, for interrupting the circuit, the contact and 20 terminal member 1 being fixed and the member 2 movable. The member 2 is contained in a horizontal bushing comprising a hollow insulating shell 3 mounted at one end in one side of a casing 4.

The casing 4 contains the fixed contacting member 1 and is carried on columns or pillars 5, 6 built of porcelain sections. The columns 5, 6 are oil-filled and may accommodate within them instrument or relay transformers or other apparatus associated with the switches as required. Further, the columns 5, 6 may be utilized as conduits for renewing, circulating and/or filtering the casing oil, in any well known manner. 25

The other end of the bushing 3 is mounted in 35 one side of an intermediate casing or junction box 7 which is carried also on columns 8 built of porcelain sections. The junction box 7 may conveniently be of a form and wall thickness which, by slight deformation allows for thermal 40 changes of dimensions in other related parts of the apparatus.

The other pair of contacts forming the double break switch is mounted in a similar manner on the other side of the junction box, and only one 45 side of the switch need therefore be described in detail.

The casing 4 may accommodate an explosion pot or oil blast arc interrupting device 9 of the known type associated with the fixed contact and terminal structure 1 which is suitably connected in the circuit to be interrupted. A detailed description of the arc interrupting device generally indicated at 9 is not necessary for a complete understanding of the present invention. 55

By way of example, an oil blast device having spaced insulating plates forming pressure exhaust passages of the type disclosed by Juhlin Patent 1,902,507 granted March 21, 1933 for Electric circuit interrupters may be used. The casing 4 is further provided with a trapped air chamber 10 to absorb the pressure pulsations set up in the oil upon interruption of the circuit.

The horizontal bushing 3 comprises two sections 11, 12, the section 11 being mounted within the casing 4 and the section 12 lying outside the casing 4, and this latter section is mounted at its other end in the junction box 7.

Running throughout the length of the bushing 3, and coaxial therewith is the insulating cylinder 13 which is closed at the casing end by means of the baffle plate 14. The baffle 14 has a central orifice 15, so that the interior of the cylinder 13 is in communication with the interior of the tank 4. Between the bushing 3 and the cylinder 13 any suitable arrangement of baffles and/or condenser type conducting cylinders may be used according to known practice.

In the interior of the cylinder 13 is mounted a bearing member 16 which forms a fixed terminal and also serves as a stuffing box for a purpose to be hereinafter described. Electrical connection is made between the member 16 and the corresponding member in the bushing on the opposite side of the junction box by means of the cylinder 21 coaxial with the cylinder 13 and the junction member 36.

Electrical connection between the member 16 and the stationary contact 1 is made by means of the movable rod contact 2 which slides through the member 16 in contact therewith, and is provided at one end with a piston head 17. The piston 17 slides in a cylinder 18 coaxial with the insulating cylinder 13 and the cylinder 18 at one end is in communication with a supply of compressed air controlled by the valve mechanism 19 situated in the junction box 7, and which will be referred to hereinafter. The cylinder 18 is closed at the other end by the contact bearing member 16 which also serves as a stuffing box, the cylinder 18 being provided with apertures 28 near this end so that communication is established between the back face of the piston head 17 and the space between the coaxial cylinders 18 and 21, which space is in communication with the compressed air supply through the valve mechanism. A metallic potential distributor 46 is provided as shown at the end of the cylinder 18.

The casing 4, the bushing 3, and the insulating cylinder 13 are filled with a suitable insulating liquid as oil, communication between the tank and the cylinder being made through the aperture 15, but there is no communication between the oil in the bushing and the oil in the tank.

When an explosion occurs on the opening of the switch in the device 9 the pressure pulsations caused thereby are absorbed by the air trapped in the chamber 10 which communicates with the tank by the aperture 22. In order that the explosion pulsations originating in the oil in the tank 4 may be further cushioned by their effect upon the oil in the bushing 3 the device shown at 23 is provided. This device 23 comprises an annular chamber, the outer and inner cylindrical walls of which are perforated at the top, and the inner wall is provided at the bottom with a series of apertures 25 over an arc, the length of which is indicated by the arrow 26 as shown in Fig. 2. A pipe 27, provided with a closing cap 28 passes through the apertures in

the top of the inner and outer cylindrical walls in a fluid-tight manner, and through this pipe oil may be introduced into the bushing and into the annular chamber 23 through the apertures 25. The upper portion of the annular chamber 5 will trap air to constitute an air cushion.

The compressed air valve mechanism situated in the junction box 7 is shown in detail in Fig. 5. The valve mechanism is contained within a casing 19 situated on the bottom of the junction box 7, and comprises an admission chamber 33 which communicates through the apertures 47 with the interior of the supporting column 8, and a discharge chamber 38 which communicates with the atmosphere through the pipe 39. The 10 interior of the column 8 is supplied with compressed air in any known manner and two admission valves 29, 30 admit compressed air to one or the other side of the piston, in the one case through the pipe 34, junction pipe 35 which 20 connects the cylinders 18 of each side of the switch in communication with each other, to the front face of the piston 17, and in the other case through the pipe 37, junction pipe 36 which 25 connects the annular space between cylinders 18 and 21 of both sides of the switch together, through this said space, apertures 28 and interior of cylinder 18 to the back face of piston 17.

The discharge valves 31 and 32 control the discharge of air from the piston cylinder 18. Thus, 30 when the admission valve 30 is open to admit air to the front of the piston the discharge valve 31 is open to allow the escape of air from the back face of the piston, the pistons 29 and 32 then remaining closed. In this case, the contacts 1 and 35 2 are closed. To separate these contacts, to open the circuit, the admission valve 29 and discharge valve 32 are opened, the valves 30 and 31 then remaining closed.

The valves are operated by means of the cams 40 and 41 mounted on a central shaft 42 which is carried on the top of a central insulating column 43, which is rotated in a well known manner by means of a push bar 45 situated at the base of the column 8. 45

Each valve is provided with the usual return spring and the admission valve stems are each provided at one end with a roller mounted on a spindle transverse to the stem, the rollers bearing on the internal surface of the hollow cam 41, 50 whilst the stems of the discharge valves 31, 32 bear on the cam surface of the disc 40.

Figure 6 shows a plan view of the arrangement of the double break switches as hereinbefore described, connected in each phase of a three-phase system. The central insulating columns 43 operating the cams 40 and 41 and enclosed within each of the junction-box supporting columns 8, are simultaneously rotated by means of a push bar 45 connecting the insulating columns with 60 the operating mechanism indicated at 44. The operation of the various switches may be controlled by individual controlling means if desired.

The connection between the push bar 45 and the central insulating column 43 is shown at the 65 foot of the central column in Figure 1, and comprises a lug on the push bar which is pivotally connected to a forked lug on the base of the insulating column. Any other convenient means for rotating the central insulating column 70 through the angle required to operate the valves may be provided.

Although the bushings 3 have been hereinbefore described as situated horizontally, they may be inclined slightly upwards towards the junc- 75

tion box, so that air leaking out of the stuffing box 16 need cause no trouble, as it will pass back along the space between the cylinders 21 and 13 and be discharged at the junction box.

5 As hereinbefore mentioned it is necessary that the switch chambers and junction box shall be insulated from the ground so as to withstand continuously line to ground potential difference. The insulation between the junction box and each 10 of the switch casings or chambers need, however, only be such as to withstand continuously approximately one half the line to line potential difference, but the insulation between the two switch chambers must be capable of withstand- 15 ing the full potential difference between the lines.

It is to be understood that the various chambers hereinbefore described as being oil-filled may be filled with any other suitable insulating fluid.

20 It should be understood that my invention is not limited to specific details of construction and arrangement thereof herein illustrated, and that changes and modifications may occur to one skilled in the art without departing from the 25 spirit of my invention.

I claim:

1. A high voltage circuit breaker of the liquid-break type comprising spaced stationary terminal structures, a casing positioned intermediate and spaced with respect to said terminal structures, a pair of insulating shells extending between and interconnecting said intermediate casing and said terminal structures, an insulating cylinder mounted within and extending longitudinally of each of said shells, an insulating liquid between said each cylinder and shell, movable contact structure disposed in said cylinders for interrupting the circuit between said terminal structures, an insulating liquid in said cylinders sealed with respect to said first-named liquid, insulating pillars for supporting said terminal structures and said intermediate casing, said pillars insulating said terminal structures and casing with respect to line potential and ground, and operating means for said contact structure mounted within the intermediate casing and its supporting pillar.

2. A high voltage circuit breaker comprising a pair of oil-filled terminal casings, insulating supports for supporting and insulating said casings with respect to line potential and ground and a third casing positioned between and spaced with respect to said terminal casings, an insulating support for said third casing likewise insulating the same with respect to line potential and ground, a pair of insulating shells interconnecting said third casing and said terminal casings, said shells containing oil sealed with respect to the oil in said casings, movable contact structure disposed in said insulating shells for interrupting the circuit, and operating mechanism for said contact structure extending into said third casing through its insulating support.

3. A high voltage circuit breaker of the liquid-break type comprising a pair of spaced terminal structures, an insulating supporting pillar for each of said terminal structures, an insulating cylinder containing an arc extinguishing liquid extending between said terminal structures, movable contact structure disposed within said insulating cylinder, a ceramic insulating shell surrounding and spaced from said insulating cylinder disposed between said terminal structures, the 10 annular space between said cylinder and shell containing an insulating liquid sealed with respect to the liquid in said cylinder, and operating means extending through one of said supporting pillars for controlling said movable contact structure. 15

4. A high voltage circuit breaker of the liquid-break type comprising a pair of oil-filled casings, stationary contact and terminal structure disposed in said casings, a casing disposed intermediate and spaced with respect to said terminal casings, a pair of insulating shells extending between and interconnecting said intermediate and terminal casings, an insulating cylinder disposed in each of said shells and extending within 25 said terminal casings, a movable rod contact mounted within each of said cylinders for coacting with said stationary terminal structure, the space between said cylinders and said shells being filled with insulating liquid sealed with respect to said terminal casings, insulating pillars for supporting said intermediate and terminal casings at substantially the same level and insulating said casings with respect to line potential and ground, and operating means disposed with- 35 in the intermediate supporting pillar.

5. A high voltage circuit breaker of the liquid-break type comprising an oil-filled casing, stationary contact and terminal structure mounted in said casing, a movable contact adapted to 40 extend within said casing to coact with the stationary contact, a hollow insulating shell within which said movable contact is operably mounted in said casing, said movable contact being enclosed and sealed with respect to the interior of 45 said insulating shell, an insulating liquid in said shell sealed with respect to said casing, and an annular expansion chamber surrounding and in communication with said shell for relieving stress upon interruption of the circuit. 50

6. A high voltage circuit breaker of the liquid-break type comprising an insulating cylinder, movable contact structure disposed in said cylinder and immersed in an arc-extinguishing liquid, an insulating shell spaced from and enclosing 55 said insulating cylinder, an insulating liquid in the space between said cylinder and shell, said liquid sealed with respect to said arc-extinguishing liquid, and means forming an expansion chamber for the liquid in said shell. 60

ARTHUR CHARLES EHRENBURG.
